UNITED STATES PATENT OFFICE

ANDREW O'ROURKE, JR., AND JOHN SPREKELMEYER, OF DALLAS, TEXAS

GRAVITY-FLOW SANITARY SYRINGE AND CABINET UNIT

Application filed May 1, 1928. Serial No. 274,198.

The present invention relates to a gravity flow sanitary syringe and cabinet unit and has for its prime object to provide a cabinet which may be built in the wall or the like and contains all the necessary parts to provide a gravity syringe.

Another very important object is to provide a structure of this nature including a tank having means incorporated therein whereby hot and cold water may be run into the tank, the tank may be easily drained and an overflow means associated with the draining means.

Another very important object of the invention resides in the provision of a cabinet with a tank therein and a glass tube disposed alongside the tank and communicating with the lower portion thereof for holding a thermometer in order that the temperature of the water in the tank may be readily ascertained.

A still further very important object of the invention resides in the provision of a structure of this nature which is simple, strong and durable, comparatively inexpensive to manufacture and build, compact and convenient in its arrangement of parts, very handy, and thoroughly efficient and reliable in use and operation.

With the above and numerous other objects in view as will appear as the description proceeds, the invention resides in certain novel features of construction, and in the combination and arrangement of parts as will be hereinafter more fully described and claimed.

In the drawings:

Figure 1 is a front elevation of the structure embodying the features of our invention showing the doors in an open position,

Figure 2 is a vertical section therethrough taken substantially on the line 2-2 of Figure 1 but showing the door closed,

Figure 3 is a horizontal section taken substantially on the line 3-3 of Figure 1,

Figure 4 is a vertical section through the tank,

Figure 5 is a vertical section taken at right angles to that shown in Figure 4 and substantially on the line 5-5 of Figure 4, and

Figure 6 is a horizontal section taken substantially on the line 6-6 of Figure 4.

Referring to the drawings in detail it will be seen that the cabinet disclosed herein by way of example includes a rear wall 5, a bottom wall 6, a top wall 7, side walls 8, and a front wall 9 having an opening 10 therein.

A door 11 is hinged at 12 to one side edge of the opening 10 to close the opening 10 and the outer surface of the door is recessed at 12 so that a mirror 14 may be disposed therein on the outside of the door. A shelf 15 is mounted in the cabinet a distance above the bottom and below the vertical center of the cabinet.

A plate or panel 16 is disposed vertically in the lower portion of the cabinet between the bottom 6 and the shelf 15 and is spaced inwardly from the front wall 9. A tank 17 of semi-cylindrical formation in horizontal section as is shown in Figure 6, is mounted to rest on the shelf 15 and has its flat wall against the rear wall 5 to one side of the center of the cabinet.

The bottom of the tank 17 is provided with a centrally located opening 19 adjacent the flat wall and end openings 20 and 21. A screen or strainer 22 is disposed in the tank over the opening 19. A pipe 23 depends downwardly from the bottom of the tank in communication with the opening 19 and has branches 24 and 25 with valves 26 and 27 therein respectively.

The branch 24 is to be connected with a source of hot water and the branch 25 with a source of cold water. A pipe 28 depends from the bottom of the tank in communication with the opening 20 and has a valve 29 therein and at its lower end terminates in a laterally disposed nipple 30 over which the end of a syringe hose 31 may be slipped.

A pipe 32 depends from the bottom of the tank in communication with the opening 21 and has a valve 33 therein and is adapted to be connected with the sewer system for draining the tank. A pipe 34 leads laterally from the lower end of the pipe 32 below the valve 33 and then rises up alongside the tank 17 and communicates with the upper portion thereof through an opening 35.

The top 36 of the tank 17 is removable. An elbow 37 leads outwardly and slightly upwardly from an opening 38 in the lower portion of the tank and has coupled thereto 5 a glass tube 39 by suitable coupling means 40.

This glass tube 39 rises up alongside the tank terminating slightly thereabove and supported at its upper end by a suitable 10 bracket 41. A thermometer 32 is disposed in the transparent tube 39 whereby the temperature of the water in the tank is readily ascertainable at all times.

The pipe 34 takes care of any overflow. 15 The hose 31 leads through an opening 43 in the shelf 15 and it may be hung, when not in use, on a hook 44 mounted on the rear wall of the cabinet adjacent the top thereof.

The hose is provided with a clamp 45 of 20 suitable construction so that the flow of water thereof may be cut off when desired. From the above detailed description it will be seen that by operating the valve 26 and 27 hot and cold water may be run into the 25 tank and the level of the water may be ascertained by the level of the water in the tube 39 and also the temperature of the water may be ascertained by watching the thermometer 32 in said tube 39.

30 Obviously the temperature of the water may be regulated by the regulation of the valves 26 and 27. If it is desired to place anything in the water this may be done by lifting the cover or top 36 as will be apparent.

Any overflow will be taken care of by pipe 34. The tank may be readily drained by opening the valve 33. After the desired amount of water has been placed in the tank 40 17 of the desired temperature, the hose 31 may be lifted off the hook 44 and, of course, the clamp 45 should be crimping the hose to prevent the flow of water therethrough.

The cabinet is adapted to be built in the 45 wall at a sufficient height to provide a gravity flow. The pipes 23, 28 and 32 are hidden by the panel 16 but the valve stems of valves 29, 26, 27 and 33 extend through this panel so that the knobs or handles of the 50 valve are accessible whenever the door 11 is open.

The nozzle or nipple 30 is also located in front of the panel 16 so that all parts of the hose 31 are readily accessible when it 55 becomes necessary to renew the same as this is obviously the only part of the apparatus which would ordinarily need renewing during the life of the apparatus.

It is thought that the construction, operation, utility and advantages of this invention will be quite apparent to those skilled in this art without a more detailed description thereof. The present embodiment of the invention has been disclosed in considerable detail merely by way of example

since in actual practice it attains the features of advantages enumerated as desirable in the statement of the invention and the above description.

It will be apparent that changes in the 70 details of construction, and in the combination and arrangement of parts may be resorted to without departing from the spirit or scope of the invention as herein-after claimed or sacrificing any of its advantages. 75

Having thus described our invention, what we claim as new is:

In a device of the character described, the combination of a cabinet comprising 80 front and rear walls, side walls, and a top and bottom wall, said front wall being provided with an opening, a door hingedly mounted on one side of said opening, a shelf 85 extending across the bottom portion of the cabinet, and above the lower side of the opening in said front wall, a vertically disposed panel located within the cabinet between said shelf and bottom wall and spaced inwardly from said front wall, a tank on the shelf, a pipe leading from the bottom of the tank through the shelf and between the panel and rear wall of the cabinet, said pipe merging into a pair of valve controlled 90 branches with the stems of said valve 95 adapted to extend through the panel, and said branches adapted for connection with sources of hot and cold water, respectively, a second pipe leading downwardly from the bottom of the tank through the shelf and 100 having a valve incorporated therein, the stem of said last mentioned valve projecting through said panel, and said second pipe terminating in a nipple adapted to extend 105 through said panel, a syringe hose engaged over the nipple, a hook in the upper portion of the cabinet on which the syringe 110 hose may be hung, a third pipe extending downwardly from the tank through the shelf and having a valve therein, the stem of 115 said valve adapted to extend through said panel, and said third pipe having a lateral branch below the valve merging into a vertical pipe extending upwardly through the shelf and communicating with the upper portion of the tank to provide an overflow.

In testimony whereof we affix our signatures.

ANDREW O'ROURKE, JR.
JOHN SPREKELMEYER.
